UNITED STATES PATENT OFFICE

ADELE BODE, OF HAMBURG, GERMANY

VACUUM CLEANER

Application filed June 29, 1928, Serial No. 289,254, and in Sweden and Czechoslovakia April 18, 1927.

I have filed applications in Sweden and Czechoslovakia, April 18, 1927, Holland and Italy, April 20, 1927, Germany, April 29, 1927, Switzerland and Austria, April 14, 1928, 5 Belgium, April 21, 1928, France, April 23, 1928, and Great Britain, April 25, 1928.

This invention relates to improvements in vacuum cleaners, and more particularly to a cleaner having a corrugated and perforated 10 suction plate disposed immediately below a vertically mounted rotary suction fan.

An object of the invention is to provide an improved motor driven vacuum cleaner having a corrugated and perforated suction plate 15 disposed immediately below a vertically mounted rotary suction fan, and embedded within a housing whose sides are bent to form rearwardly extending passages from the front of the suction plate to the rear thereof.

20 A still further object of the invention is to provide an improved motor driven vacuum cleaner having a corrugated suction plate formed with a plurality of spaced air inlet passages, whereby air and dirt may be sucked through said passages and discharged into the dirt collecting bag adjacent the motor driven impeller.

Other objects will appear as the description proceeds.

30 In the accompanying drawings which form a part of my application:

Figure 1 is a sectional view taken on the line 1—1 of Figure 2.

Figure 2 is a side elevation of the vacuum 35 cleaner, showing the same partly in section.

Figure 3 is a perspective view of the vacuum cleaner, showing a portion thereof in section.

Like characters of reference are used 40 throughout the following specification and the accompanying drawings to designate corresponding parts.

My improved vacuum cleaner comprises a housing 1 which supports a centrally located 45 motor housing 2, in which a suitable motor is received. The lower portion of the motor housing 2 is extended outwardly to form a fan housing 3. A transverse partition plate 4 separates the motor housing from the fan 50 housing and serves as an additional bearing

for the shaft 5 of the vertically mounted suction fan 6.

A corrugated suction plate 7 is mounted in the housing 1, with the corrugations extending transversely thereof. Air passages 55 8 are formed through the forwardly extending surfaces of the corrugations, so that air and dirt may readily be sucked through the same. The housing 1 is rounded at its opposite sides and forms the rearwardly extending 60 air passages 9, the purpose of which will later be described.

A rubber brush 10 will be removably secured at the front end of the housing 1, and may be notched as at 11, and serves to draw 65 the hairs or threads as they lie free on the surface, and roll them up so that they may be readily drawn into the cleaner.

A guide roller 12 is supported between the brackets 13 at the rear of the cleaner, in such 70 a manner that the cleaner may pivot on the same.

The handle 14 is removably secured at 15 to the motor housing 2. A dust collecting bag 16 is supported between the handle 14 and the discharge outlet 17 connected with the fan 75 housing 3.

The mode of operation of my improved 80 vacuum cleaner will now be described. When the motor is in operation, the fan 6 will draw the air and dirt up from below the corrugated suction plate, and up through the air passages 8 formed in the forwardly extending portions of the plate and be discharged through the discharge outlet 17 into the dust 85 collecting bag 16. The air and dirt which passes through the passages near the back of the plate will be delivered immediately to the dust bag, but the air and dust entering the forward passages will be discharged transversely along the corrugations on the upper side of the plate and back through the side 90 passages 9 and then sucked by the fan to the outlet 17 and forced into the dust bag.

It will be obvious that many minor changes in detail of construction may be resorted to without departure from the spirit of the invention.

Having thus described my invention, what 100

I claim as new and desire to secure by Letters Patent of the United States is:

- 5 1. A device of the character described comprising a housing, a perforated corrugated suction plate carried thereby, rearwardly extending passages formed in said housing at the ends of said plate, a motor driven fan disposed above said plate and supported on said housing, and a dust collecting bag in communication with said fan.
- 10 2. A device of the character described comprising a housing, a perforated corrugated plate carried thereby, said perforations being formed in the forwardly and upwardly extending flanges of the plate, rearwardly extending passages formed in said housing at the opposite sides of said plate, a motor driven fan disposed above said plate and supported on said housing, a brush removably carried at the forward edge of said plate, a bearing roller carried at the rear of said plate, a dust bag in communication with said fan, and a handle for moving said device.

In testimony whereof I affix my signature.
